G. MARSDEN

VENDING MACHINE

Filed Sept. 15, 1925

INVENTOR:

GEORGE MARDEN,

By: Otto de Ruyger,
his Atty.

UNITED STATES PATENT OFFICE.

GEORGE MARSDEN, OF LOS ANGELES, CALIFORNIA, ASSIGNOR TO DEPENDABLE AUTO PARTS COMPANY, OF LOS ANGELES, CALIFORNIA.

VENDING MACHINE.

Application filed September 15, 1925. Serial No. 56,524.

This invention relates to devices used for vending small articles mechanically by the intervening of a coin or the like.

One of the objects of this invention is to provide a vending machine of a simple form to give the least trouble.

Another object is to provide discharging mechanism by which articles to be vended are removed from under the remaining piles 10 or columns by the automatically returning coin-holding trigger or handle-member.

Another object is to provide a displaying drum by which the articles to be vended are moved in a circular path during the vending 15 operations, having a pocket in the supporting base within the path of the displayed articles and of a depth to receive a desired number of the stored articles preparatory to being discharged from the vending machine.

Another object is to provide a supporting base for a vending machine with such a pocket, and an opening in connection therewith through which the lowered articles 20 may be discharged from the pocket.

Another object is to provide a receiving platform below such an opening spaced below the underside of the base to such an extent to allow a moving of the separated articles between the base and the platform in 25 the direction of another opening from which such separated and discharged articles may be taken by an operator.

Another object is to provide a coin-controlling and holding handle-member movable in the space between the base and the platform, whereby the separated articles may be moved from the platform into the final opening, and which handle-member serves also to rotate the drum with the 30 stored articles to bring the different upright columns of stored articles in the drum over the pocket in the top surface of the base preparatory to being separated and discharged from the stored articles in the vending machine by the returning movement of the handle-member.

Another object is to provide a yielding closing gate or valve before the discharging chute to check the discharging movement 40 so as to keep the discharged articles from falling to the ground.

Other objects will appear from the following description and appended claims as

well as from the accompanying drawing, in which—

Fig. 1 is a front elevation of the vending machine embodying my invention.

Fig. 2 is a fragmentary horizontal section partly through the storing drum in conjunction with a top plan view of the handle-member, to illustrate the relative positions of the different operating parts.

Fig. 3 is a top plan view of the base member of the vending machine with the handle member within the base-member, and a portion of the operating spider just above the base member.

Fig. 4 is a fragmentary vertical section through the operating mechanism of the vending machine, approximately on line 4—4 of Fig. 3.

Fig. 5 is a fragmentary section similar to the illustration in Fig. 4 with the operating parts slightly moved to an advanced position.

Fig. 6 is a similar section as illustrated in Figs. 4 and 5 with the parts still further advanced in the operating movement.

Fig. 7 is a fragmentary side elevation of the base member with a closing valve over the discharging chute.

Fig. 8 is a fragmentary vertical section through the drum illustrating the engaging position of the spider.

To assure a discharging and vending of articles in certain quantities, and to eliminate or avoid as far as possible a breaking or crushing of articles during the vending operation, or to avoid an eventual clogging of the vending machine, a provision is made to separate and select a desired quantity of and from the stored articles preparatory to a final discharging of the separated and selected articles.

The coin-controlled lever 9 serves preferably to discharge the selected and separated articles, and most advantageously during the returning movement of the lever to its inoperative position. The returning of the lever is preferably made automatic. In Fig. 2, a spring 10 is indicated in a position that it may return the lever 9 back to normal inoperative position, the lever being in this illustration indicated in its advanced position. This lever is mounted swingably 105 around the central connecting bolt 11. The

bolt 11 serves to hold the whole vending machine together, between the bottom-plate 12 and the top-plate 13. A casing 14 of transparent material, such as glass, is inserted 5 between the base-member 15 and the top-plate 13, so that stored articles in the vending machine may be seen through the casing from the outside, as indicated in the illustration in Fig. 1.

10 A drum 16 is provided to rotate in a horizontal plane around the vertical bolt 11. As illustrated in Figs. 1, 2 and 8, the drum is made of sheet material, consisting of the vertically disposed trough-like portions 17, 15 interconnected over the outside by the strips 18 clinched over the outer edges of the portions 17, and centrally connected by disc-like members 19. The lowermost ends of the trough-like portions are preferably extended 20 beyond the lowermost central connecting plate 19, so that the different prongs 20 of the operating spider-plate 21 may engage and project into the space between the different vertically disposed troughs, to allow 25 a transmitting of the rotating movements of the operating spider 21 to the storing drum.

The base-member 15 is provided with a separating and selecting recess 22, into which the lowermost articles are caused to drop as 30 they pass over this recess in the circular path of their movement in the drum. This recess 22 is made of such a depth to receive a desired number of articles out of the particular vertically disposed trough just positioned 35 over the recess in the base. By making the depth of the recess equal to the thicknesses of the desired number of articles wanted at one operation, such a selecting and separating is thereby predetermined so as to assure 40 a discharging of the correct quantity of articles. The side walls of the recess are preferably shaped so that the separated articles are suitably shifted in a sidewise direction while advanced for the discharging movement, as indicated at 23 in Fig. 3. By the curving of the edges 23 as illustrated, the separated articles are moved away from the circulating path of the rotating drum, while the articles remaining in the drum are kept 45 above the base by the portion 24 of the base, just beyond the recess 22.

The separated articles are pushed from the recessed portion of the base until the front edge of the separated articles drops down upon the lever in the manner illustrated in Fig. 5, as indicated at 25. On advancing the lever 9 and thereby the spider 21 with the drum 16 still further, the rear edge of separated articles is caused to drop from 55 the recessed portion 22 of the base member 15, as indicated at 26 in Fig. 6. The separated articles then drop from the lever 9 as the lever is still further advanced, so that the separated articles come to rest on the plat- 60 form 27 of the bottom plate 28.

Since the operating lever 9 is advanced against the tension of the spring 10, on releasing the lever it automatically returns to its normal inoperative position. In so returning to its inoperative position, however, the lever comes to hit the separated articles resting on the platform 27, and, by the force of the spring 10, the lever pushes and shoots the separated articles from the platform into the chute 28, from which it may 75 be taken by the operator.

To prevent a moving of the drum, more particularly the vertically disposed troughs, for a distance more than from one trough to the next, a suitable checking mechanism has 80 been interposed. Without any checking means it might be possible to jerk the operating lever 9 suddenly and fast enough to cause the drum to move beyond a predetermined distance, and thereby allow a discharging of articles from the drum of a greater than a desired quantity. The lever 9 is therefore provided with an extension-end 30, as illustrated in Figs. 2, 4 and 5, having 85 a downwardly bent portion 31. A check, in 90 form of a rivet or the like, is provided in the base member 15, as indicated at 32, for a movement in a vertical direction, and so as to extend into the path of the spider-prongs 20. The bend or dip 31 of the operating 95 lever 9 is arranged so that the rivet or check is thereby allowed to drop long enough to allow one of the spider-prongs 20 to pass over this point as the lever is advanced.

An interconnection is normally established 100 between the operating lever 9 and the prongs, or one of the prongs 20 at a time, by interposing a coin or the like in the slot 34 so as to engage with the prongs 20 of the operating spider 21, as indicated at 29 in Figs. 4 105 and 5. The operating spider is therefore also advanced together with the advancing of the operating lever 9. A quick jerking of the lever might therefore cause a moving of the spider therewith of the drum beyond a 110 predetermined distance.

However, no matter how quick the operating lever 9 is moved, the check 32 is always forced to a point above the surface of the base and into the path of the prongs 20 115 of the operating spider that only one prong 20 can pass at a time, and that is only at the moment when the dip 31 of the lever 9 passes below the check 32. This is illustrated in Figs. 4 and 5, the prong 20_a being in Fig. 4 at 120 a point just after the check 32 with the check 32 still held on the high point 30 of the lever 9; while, in the advanced position of the lever 9 in Fig. 5, the dip 31 of the lever 9 having 125 passed the check 32 so as to allow the prong 20_a to pass the check, however, the check 32 having been forced back up to above the base 15 so that the next prong 20_b could not very well pass the check during 130 this operation of the lever 9. The

check, in addition to easily acting by gravity, to assure a proper operating, especially a proper dropping, to allow a passing of one of the prongs, is provided with a spring 33.

The gate 36 is pivotally connected to the lugs 35 on the base 15 at 37, as illustrated in Fig. 7. The upper extension-end 38 serves to facilitate an opening of the gate or valve 36, to enable the operator to remove the separated and discharged articles from the chute 28.

Having thus described my invention, I claim:

1. In a vending machine, a drum for movably storing articles to be vended, an operating lever having means to interconnect the lever with the drum by the insertion of a coin or the like for moving the drum, fixed means to receive and hold a desired number of articles from the drum and adapted to hold such articles so that said operating lever will discharge the articles so held by a return of the lever to its inoperative position.

2. In a vending machine, a drum for movably storing articles to be vended, an operating lever having means to interconnect the lever with the drum by the insertion of a coin or the like for moving the drum and thereby moving certain of the stored articles into a fixed separating compartment, fixed means to receive and hold such separated articles so that said operating lever will discharge the articles by a return to its normal inoperative position.

3. In a vending machine, a drum for storing articles to be vended, an operating lever having means to interconnect the lever with the drum by the insertion of a coin or the like for moving the drum and thereby moving certain of the articles into fixed separated position, fixed means for receiving and holding the separated articles in discharging position, and means for receiving and holding the articles after the articles have been removed from the discharging position by a return of the operating lever to its normal inoperative position.

4. In a vending machine, a drum for storing articles to be vended, means to allow certain of the stored articles to drop from the stored position in the drum to a lower level into a fixed separated position, fixed means to allow the separated articles to drop to a still lower position free of and below the drum, an operating lever having means to receive and hold a coin or the like for interconnecting the lever with the drum for moving the drum and thereby the stored

articles to occupy the different positions named above and adapted to discharge the articles from the last-named position by a returning to its normal inoperative position.

5. In a vending machine, a drum for storing articles to be vended, a base for supporting the drum having a recess into which certain of the articles may drop from the drum in operative contact with the drum and having an opening at the termination of the recess, a platform in the base just below the said opening and spaced from the underside of the base to such an extent that the said certain articles may pass from the top of the platform under the underside of the top of the base for a discharging operation, and an operating lever swingably disposed in the space between the top of the said platform and the underside of the base and adapted to push said articles from the platform, the operating lever having means to receive and hold a coin or the like for interconnecting the lever with the drum for moving the drum and thereby the stored articles.

6. In a vending machine, a drum for storing articles to be vended, a base for supporting the drum, an operating lever for actuating the drum and thereby the stored articles and having a drop portion, and a checking pin loosely disposed in the base and adapted to pass over and through said drop portion extending to a point to control the movements of the drum so that the drum is movable only to a certain extent in one operation of the lever, the operating lever having means to receive and hold a coin or the like for interconnecting the lever with the drum for moving the drum and thereby the stored articles.

7. In a vending machine, a drum for storing articles to be vended, a base for supporting the drum and having a recessed portion terminating before the discharging opening at a point over which the stored articles in the drum must pass, and an operating lever disposed below the recessed portion and below the discharging opening and having coin holding means by which the drum can be actuated so that certain of the articles will first drop into the recessed portion and then with the front edge upon the operating lever so that the rear edge of the articles will be caused to drop from the recessed portion before the front edge of the articles will drop from the lever as the lever and thereby the drum are advanced further.

In testimony that I claim the foregoing as my invention I have signed my name.

GEORGE MARSDEN.
